APPARATUS FOR EXTRUDING SEAMLESS BRASS AND COPPER TUBES

Application filed January 17, 1930. Serial No. 421,344.

This invention relates to an apparatus for producing tubes of brass, copper or other metals by forcing molten metal through a die, congealing said metal in tubular form, and continuously drawing away the solid tube thus formed.

One object of this invention is to provide an apparatus of the above nature including a vessel containing molten metal and located within a furnace, said vessel having a die plug at its lower end through which the molten metal flows under high pressure into a tubular casing.

A further object is to provide an apparatus of the above nature in which the molten metal flowing from said die plug is continuously congealed within a surrounding casing and drawn out therefrom by a draw bench or other suitable device.

20 A further object is to provide an apparatus of the above nature in which the congealing casing is provided with an end cap to prevent the escape of molten metal from the end of the casing at the beginning of the tube forming process.

25 A further object is to provide an apparatus of the above nature whereby seamless tubing of metal, such as copper and copper alloys, may be produced directly from molten metal without making cores, casting or scalping billets, and in which the repeated pointing, annealing and drawing operations formerly required in the production of tubes are entirely eliminated.

30 A further object is to provide an apparatus of the above nature which will be relatively simple in construction, inexpensive to manufacture, easy to manipulate, compact, and very efficient and durable in use.

40 With these and other objects in view, there has been illustrated on the accompanying drawings one form in which the invention may be conveniently embodied in practice.

Fig. 1 represents a longitudinal vertical 45 sectional view taken through the apparatus.

Fig. 2 is a fragmentary horizontal sectional view of the same.

50 Fig. 3 is a fragmentary vertical sectional view taken through the delivery end of the apparatus.

Fig. 4 is a transverse fragmentary sectional view taken along the line 4—4 of Fig. 3, looking in the direction of the arrows.

Fig. 5 is an end view of the outlet die plug.

Referring now to the drawings in which like reference numerals denote corresponding parts throughout the several views, the numeral 10 indicates a pot or vessel which is preferably constructed of heat resistant metal, such as the type of steel known as 60 "Alleghany ascoloy 44."

The vessel 10 is provided at its top with a removable cover-plug 11 through which molten metal 12 may be poured therein. The numeral 13 indicates a pipe through which compressed air may be supplied for forcing the molten metal 12 out of the pot through a bottom outlet die plug 14 having a conical outer surface for releasably fitting within a conical opening 15 in the bottom of the vessel 10.

The die plug 14 is provided with an elongated mandrel 16 formed integral therewith and extending away from said vessel 10. The mandrel 16 is surrounded by a cylindrical casing 17, the outer end of which is provided with a plurality of outwardly extending lugs 18 for detachable engagement with a plurality of inwardly extending lugs 19 formed in a cap member 20, said cap member 80 having a shoulder 21 for fitting loosely against the annular extremity 22 of the casing 17.

In order to cool the end portion of the casing 17, provision is made of a water-jacket 23, through which water is circulated by means of an inlet pipe 24 and an outlet pipe 25. By the use of the water jacket 23, the molten metal 12 flowing into the casing 17 will be caused to congeal in tubular form in 90 the space between the mandrel 16 and the outer portion of the tubular casing 17 surrounded by said water jacket 23. The outlet die plug 14 has an arc-shaped curved lower aperture 26 (see Fig. 5) for connecting the 95 interior of the vessel 10 with the tube forming space within the casing 17.

In order to center the mandrel 16 accurately within the casing 17, provision is made of a plurality of adjustable screw bolts 27, four 100

in number in this instance, which are adapted to be screwed into corresponding threaded apertures in the casing 17 at a point intermediate between the plug 14 and the cap 5 20 where the metal is still in the molten condition.

In order to detachably hold the casing 17 tightly against the opening 15 of the vessel 10 surrounding the die plug 14, the casing 10 17 is provided with an enlarged collar 28 adapted to be embraced by a pair of elongated jaws 29 forming an integral part of said vessel 10, said jaws 29 having inturned ends 30, as clearly shown in Fig. 2. After 15 the collar 28 of the casing 17 has been arranged within the jaws 29 in the position shown in Fig. 2, a vertical U-shaped wedge 31 is adapted to be driven downwardly between the collar 28 and the inturned ends 20 30 of the jaws 29 until the casing 17 has been forced against the vessel 10 with a sufficient degree of tightness to prevent leakage of molten metal.

The vessel 10 is preferably enclosed with 25 in a furnace 32, preferably oil-burning, for maintaining the temperature in the vessel 10 above the melting point of the metal being employed. The exhaust gases from the burning of the oil are adapted to leave the furnace 30 through a horizontal passage 33 controlled by a damper 34.

In order to permit the entire length of the casing 17 to be heated by the hot gases in the furnace 32 when the molten metal is 35 first poured into the vessel 10 so that said molten metal will completely fill the casing 17 and cap 20, the furnace 32 is provided with a reduced section 34a, in which a rectangular end-door 35 and a U-shaped 40 inner door 36 are located. The door 36 is located just inside the position of the water-jacket 23 and is connected by a chain 37 to said end-door 35, said chain being adapted to ride over a pair of pulleys 38 and 39, the latter pulley having an operating handle 40.

By means of this construction it will be seen that when the operator desires to close the door 36 and open the door 35, it will only be necessary to rotate the handle 40 in a 50 counter-clockwise direction, the weight of the door 36 causing it to move downwardly into the position shown in Fig. 3, after which water will be supplied to the jacket 23. The heat being thus removed therefrom the end 55 of the casing and the cap 20 will then be rapidly cooled and the metal therewithin will be congealed to form a solid plug 41 which may be readily engaged by the prongs of a draw-bench, not shown. Any air contained in the 60 casing will escape through the loose joint between the cap shoulder 21 and the casing extremity 22.

Operation

45 In operation molten metal 12 will first be

poured into the vessel 10 to the desired level and the cover plug 11 clamped securely in position. The doors 35 and 36 will then occupy the relative positions shown in Fig. 1, the water jacket 23 being empty. Com- 70 pressed air will then be admitted through the pipe 13 and the metal will flow rapidly through the aperture 26 in the die plug 14 into the space in the casing 17 surrounding the mandrel 16, completely filling the casing 75 17 and cap 20.

The operator will then rotate the handle 40 in a counter-clockwise direction causing the U-shaped door 36 to drop and the rectangular outer door 35 to rise, said doors then occupying the relative positions shown in Fig. 3. A supply of cooling water will then be admitted to the jacket 23 surrounding the end of the casing 17, through the inlet pipe 24, said water being withdrawn through the outlet pipe 25. This will cause the metal within the cap 20 and the end portion of the casing 17 to rapidly congeal, as shown in Fig. 1. The operator will then twist the cap 20 until the lugs 19 thereon are out of alinement with the lugs 18 on the end of the casing 17, whereupon the cap may be readily removed by pulling it outwardly.

The tongs of the draw-bench will then be clamped over the solid plug 41 forming the end of the tube, and the completed seamless tube will be continuously drawn out of the casing 17 as rapidly as it is congealed therein.

It will be understood that casings and mandrels of various different sizes may be 100 interchangeably connected to the apparatus in order to produce a tube of any desired interior and exterior diameters.

While there has been disclosed in this specification one form in which the invention may be embodied, it is to be understood that this form is shown for the purpose of illustration only, and that the invention is not to be limited to the specific disclosure, but may be modified and embodied in various other forms without departing from its spirit. In short, the invention includes all the modifications and embodiments coming within the scope of the following claims.

Having thus fully described the invention, what is claimed as new and for which it is desired to secure Letters Patent, is:

1. In an apparatus for continuously casting a metal tube, a vessel containing a supply of molten metal, a casing connected with said vessel, a mandrel within said casing, a water jacket on the outer section of said casing to cause the metal to congeal in the outer end thereof, whereby a solid tube may be continuously drawn from said casing, said vessel and casing being enclosed by a furnace for maintaining the temperature of said metal above the melting point, and a sliding door in said casing adapted to cut off said 115 120 125 130

water jacket and the outer section of said casing from the hot gases of said furnace.

2. In an apparatus for continuously casting a metal tube, a heated vessel containing a supply of molten metal and having an outlet in its lower portion, a tubular casing connected to said vessel and surrounding said outlet, an apertured die plug fitted into said outlet, an elongated stationary mandrel set 10 cured to said die plug, means to cause said metal to congeal in tubular shape in said casing around said mandrel, whereby the congealed tube may be continuously drawn out of said casing.

15 3. In an apparatus for continuously casting a metal tube, a heated vessel containing a supply of molten metal and having an outlet in its lower portion, a tubular casing connected to said vessel and surrounding said outlet, and apertured die plug fitted into said outlet, an elongated stationary mandrel integral with said die plug, means to cause said metal to congeal in tubular shape in said casing around said mandrel, whereby the congealed tube may be continuously drawn out of said casing.

20 4. In an apparatus for continuously casting a metal tube, a vessel containing a supply of molten metal, a casing connected with said vessel, a mandrel within said casing, means for cooling said casing to cause the metal to congeal in the outer end thereof, whereby a solid tube may be continuously drawn from said casing, and a cap member for initially 25 closing the outer end of said casing and causing the formation of a solid plug on the extremity of said tube when the molten metal is first admitted to said casing.

25 5. In an apparatus for continuously casting a seamless metal tube, a casing having a stationary mandrel located therewithin, means for supplying molten metal to one end of said casing, said metal being caused to congeal into tubular shape within said casing and around said mandrel, whereby said congealed tube may be continuously drawn out 40 of the other end of said casing.

6. In an apparatus for continuously casting a metal tube, a casing having a stationary mandrel located therewithin, means for supplying molten metal to one end of said casing, means for cooling said casing to cause the metal to congeal into tubular shape around said mandrel, whereby said congealed tube may be continuously drawn out of the other end of said casing, and adjustable means in said casing for engaging said interior mandrel to vary the position thereof.

55 7. In an apparatus for continuously casting a seamless metal tube, a heated vessel containing molten metal, said vessel having a side outlet in its lower portion, a casing having an enlarged inner end surrounding said outlet, a mandrel within said casing, said vessel having a plurality of jaws extending lat-

erally therefrom around said casing, said jaws having inwardly extending lugs for engaging said casing, and a U-shaped wedge member fitting around said casing and adapted to be driven between said enlarged inner end 70 and said lugs, whereby said casing will have a tight joint with said vessel.

8. In an apparatus for continuously casting a seamless metal tube, a heated vessel containing molten metal, said vessel having a side outlet in its lower portion, a casing having an enlarged shoulder surrounding said outlet, a mandrel within said casing, said casing having a plurality of jaws extending laterally therefrom around said casing, said 80 jaws having inwardly extending lugs for engaging said casing, and a U-shaped wedge member fitting around said casing and adapted to be driven between said enlarged shoulder and said lugs, whereby said casing will 85 have a tight joint with said vessel.

9. In an apparatus for continuously casting a seamless metal tube, a heated vessel containing molten metal, said vessel having a side outlet in its lower portion, a casing having an enlarged inner end surrounding said outlet, a mandrel within said casing, said casing having a plurality of jaws extending laterally therefrom around said casing, said jaws having inwardly extending lugs for engaging said casing, and a wedge member fitting around said casing and adapted to be driven between said enlarged inner end and said lugs, whereby said casing will have a tight 95 joint with said vessel.

In testimony whereof, I have affixed my signature to this specification.
